UNITED STATES PATENT OFFICE.

CHARLES W. FELT, OF SALEM, MASSACHUSETTS.

IMPROVEMENT IN TYPE-SETTING MACHINES.

Specification forming part of Letters Patent No. 38,955, dated June 23, 1863.

To all whom it may concern:

Be it known that I, CHARLES W. FELT, of Salem, in the county of Essex and State of Massachusetts, have invented a spacing and justifying machine for operating on lines of type, and intended to be used in conjunction with a type setting machine; and I do hereby declare that the following, taken in connection with the drawings which accompany and form part of this specification, is such a description of my invention as will enable those skilled in the art to practice it.

Throughout the drawings similar letters refer to similar parts.

Figure 1, Sheet 1, is a front elevation of my machine; Fig. 2, Sheet 2, a plan; and Fig. 3, Sheet 3, a cross vertical section taken in the plane of the lines Z Z, seen in Figs. 1 and 2, and exhibiting the machine in elevation beyond the cutting-plane.

Other drawings (marked Details 1 2 3, &c.) will be referred to hereinafter as occasion may require, and are details of parts of the machine which are lettered, as above described.

Throughout this specification I use the terms "spacing" and "justifying" in their ordinary technical signification among printers, "spacing" signifying the operation of securing a nearly equal distance between the words, and "justifying" making the lines of type of the same length.

In the practice of my invention I introduce, in setting up the type in lines, whether by hand or machinery, certain peculiar spaces between the words, but not at the ends of the lines, which I term "machine-spaces." These are inserted in the place of the spaces ordinarily employed, and are used as a means for indicating to the mechanism where spaces of the common kind should be inserted to accomplish the purpose for which this invention is made. The line of type, with its machine-spaces, is fed into or placed in a channel having its top open for insertion and extraction of spaces, its bottom removable, so that each line of type, when spaced and justified, can be placed upon a proper galley, and its sides adjustable, for the purpose of accommodating type of different sizes—as for instance—"brevier," "nonpariel," &c.; also having two stops—one at each end of the line of type—that near the end of the channel at which the type are introduced being movable only so far as to

admit of the entrance of the type, after which it acts upon them as a fixed stop, and the other stop, at the opposite end of the line, being movable in the direction of the length of the line of type, against which it is constantly pressed, and acting by the position given it by change in the length of the line of type to indicate, by means of wedges, levers, toggles, or other suitable devices, the necessary operations to the spacing and justifying mechanism. A box containing spaces of the ordinary kind is located above the type-channel, so as to be capable of being moved over the line of type, and of being checked at the machine-spaces, at which times the type on each side of the space which is acting as a check are firmly clamped, the space being included with the type nearest the stationary stop, and clamped with them to a fixed bar, while the type on the side of the space nearest the movable stop are clamped to a movable bar, by the movement of which, and the clamping aforesaid, a separation takes place in the line of type in which a "space" can be inserted by a plunger made to operate on one of the spaces contained in the box. The space-box, after the withdrawal of the plunger before referred to, is moved along and these operations repeated till there is no longer room for the reception of the ordinary spaces. When the line is so filled, the machine-spaces are extracted, and if the line is filled exactly or is justified, then for each machine-space extracted, a common space of the same thickness is inserted. As the machine-spaces are extracted, they are pushed out of the grasp of the pinchers, by a suitable mechanism for that purpose, into a box arranged to receive them. To provide for justifying the line to a very minute fraction of an inch, where it falls short of being its proper length by less than the thickness of the spaces used in filling the line, and which, for illustration, I shall assume to be "hair-spaces" of brevier, which are five two-hundred-and-seventieths of an inch thick, as are also the machine-spaces. The space-box is provided with another set of spaces, slightly thicker, and which I shall assume to be "five-em spaces," which are six two-hundred-and-seventieths of an inch thick. When in this condition of things there exist one or more two-hundred-and-seventieths of an inch of the proper length of the line unfilled, the indicating mechanism changes the

position of the space-box so that the five-em spaces are over the type-channel and subject to the action of the plunger, and as each machine space is extracted a five-em space is inserted in its stead, which increases the length of the line one two-hundred-and-seventieth of an inch. This operation is repeated till the line is filled to less than the one two-hundred-and-seventieth of an inch of its exact proper length, when the indicating mechanism causes the position of the space-box to be shifted so as to bring the hair spaces into position to be inserted in the line wherever the machine-spaces are drawn out—an operation which does not change the length of the line, the spaces extracted and the spaces inserted being equal in thickness and number. In the case assumed for illustration it is evident that but four five-em spaces could be required for justification of a line, since if there were a space of five two-hundred-and-seventieths of an inch to be filled in the line it would be supplied with a hair-space. Spaces of different thicknesses than those named may be used, and more sets than two may also be employed, as it is evident that the principle illustrated may be made the subject of more extended combinations.

The piece A is the main support of the machine, which is suitably sustained in position, so that the whole of the machine, with exception of a few parts which require connection with fixed points, is capable of being moved upon A as on a slide for the purpose of bringing the type-channel of this machine about with the "stick" of the type-setter. Cross heads B surround A, and are capable of freely moving thereupon, while they carry the slide C, on which the space-box H and other parts of the machine are moved. A rigid bar unites the cross heads B, to which bar the slide D is fixed, on which the movable bottom of the type-channel is drawn up and down. Other pieces, E, are fixed to the said cross-bar, and serve as guides to the ends of the said movable bottom, and also to support the upper sides, a, of said channel and other parts of the machine which move on A. The movable bottom of the type-channel is represented in Detail 1, as a section taken in line Z' Z', Sheet 1, and in elevation beyond, and is a T-shaped piece connected by clasps F to slide D, the top G of said piece forming the rest for the plain ends of the type. The lower sides of the channel are the pieces b and c, which are connected to G, b being a plain bar so arranged that an aperture exists between the parts, in and through which an instrument may be made to operate upon the line of type to remove it from G to the galley. To effect this removal of the type, the bottom G and the parts immediately united therewith are drawn downward, taking with them the line of type by means of the hold which the piece c has on the type by its edge or lip fitting in the nicks formed in the type-bodies, which hold may be assisted and the type steadied by facing c with any suitable yielding material, as shown at d. The piece c is so ar-

ranged that a vertical movement may be given to it when G is drawn down to its lowest position, and provision is also made to allow a slight lateral movement of c. These two movements combined withdraw c from the nicks in the type and below the type-holding surface of G, so that the whole line may be left free for removal upon the galley. The jaw c is made to act upon the line of type to hold it together, and to cause it to move with G by the action on the jaw of spring e. When G is in its highest position, the type-channel is formed by the upper sides, a, the lower sides b and c, and the bottom G. The top of the channel is open and so are both its ends, but at one end—that at which the type are introduced—there is a catch-spring, R, which yields to admit the introduction of the type, and then acts to prevent any movement of them toward the spot from which they enter. The machine-spaces which are set up in the lines of type I prefer to make of steel and of the form shown at t' in Detail 2. These rest with their shoulders on the upper edges of a, when the plain ends of the type rest on G. Upon the slide C is located the piece I, the screw h passing through a slotted hole therein and holding it to C, while the springs i act against stops in C to keep it against other stops, x'', in C. To the end of a slide-bar in I, which is arranged so as to operate as a clamp upon the movable stop f when desired, a bar, j, is fixed so as to be movable with I. By movement of piece n the clamping and unclamping of the movable stop f with reference to I and the bar j is effected. The shaft k has fixed upon it two radius bars or rockers, l and m, to the first of which power is applied to move the latter, which compresses the spring g, surrounding the guide-spindle of the indicator-stop f. The reaction of this spring keeps the end of the rocker pressed constantly toward the indicator-stop f, and this against the line of type whenever the parts are left free to be moved by the elastic force of the spring. The forked end of m plays between two bent studs, o, which are inserted in I, and are so located and shaped that m will strike against them in the last part of its vibration, and will then move I against the resistance of its spring, i, and with it the movable bar j and the indicating-stop f, the latter having been clamped by movement of n to I and bar j previously to the contact of m with o. It is obvious that in setting up a line of type there will be some customary or practical limit to the difference between the length of the line as it is first set up and the length of the space it is intended to occupy in the form, which is the length to which the line is extended by spacing and justification. It is intended that the distance between m and where it strikes against o should exceed such a probable maximum limit, so that the only effect of the insertion in the type-channel of lines of type ranging between the probable minimum length to which such lines might be set up and the

absolute length to which it is intended to have all the lines of any given form justified will be a compression of the spring g to varying degrees. The piece L, Detail 3, rests upon and is connected to C in such a manner as to be free to move upon it against the action of spring p , similarly to that described for piece I. To L is connected a clamping mechanism, which operates, by movement of piece q , to clamp the movable bar j to the type nearest the indicator-stop f and next adjacent to the machine-space, against which the pawl p' is acting as a stop, as will be further explained beyond. A stationary bar, r , is fixed to any convenient immovable part of the machine or its framework, to which bar the machine-space which is at the time acting as a stop and the type nextadjacent to it on the side nearest the fixed stop R are clamped by the clamping mechanism illustrated in Detail 4 as connected to M, which rests upon C in a manner similar to L and I.) This clamping mechanism is made to operate by movement of piece s . Now, when m strikes against o it will be evident that the line of type must be separated at the machine-space, because of the connection of the type next the machine-space on the side of the indicating-stop with the piece I by means of the movable bar j , and that the separation will take place even though the parts of the line adhere with considerable tenacity, for the machine-space which is clamped is firmly retained from following the movement of that part of the line which is clamped to the movable bar. The line is thus separated to afford facility for the insertion of spaces between the words of which it is composed, thereby to accomplish its spacing and justification.

The mechanism of the clamps connected with L and M is best explained by reference to Details 3 and 4, as well as to the general drawings. The clamping mechanism connected with I is not detailed, but is merely so modified from that illustrated in Details 3 and 4 as to clamp the indicating-stop f to the piece I. The box H , which contains common spaces, and the box N , which receives machine-spaces, are connected to a carriage-frame, the principal parts of which are indicated by t . The box H is arranged so as to slide across the frame t on ways x' at right angles with the direction in which t moves upon C. The amount of this movement is such that the hair space part O or the five-em space part P of the box will be directly over the type-channel.

There are no means illustrated in the drawings for imparting movement to the carriage t to move it over the line of type. One of the means which I propose to employ for this purpose is the use of a spring or weight to move the carriage toward the stationary stop, checking it at each machine-space, for a purpose hereinafter explained, by means of the mechanism shown in Detail 7.

One of the uses which the machine-spaces serve, when set up in the line of type, is that of the teeth of a rack, against which the pawl

p' impinges to check the onward movement of the carriage till the pawl is tripped by a positive movement, given at the proper time, and by any suitable mechanism to the lever q' , the pawl being at all other times kept in position to come into contact with the machine-spaces t' by the action of spring r' . The carriage t is thrown back to its starting-point toward the indicating-stop by the action of mechanism which is caused to operate by the indicating mechanism.

While I have indicated the best form known to me for the machine-spaces t' , I would remark that these may be so much modified as to fall short of the boundaries of the type when they are in place in the line, in which case the pawl would fall into the space left between two type, and would act directly on the type as a check. This would probably indent the type, but the indentation could be prevented, in some measure, by detaching the pawl from the carriage and causing it to be moved to the check, and to be clamped in that position before the carriage brought up against it. The carriage t incloses L and M, which are thus made to move along the line of type with the space-boxes and to perform their appropriate functions on the type in the line. The channels O and P of the space-box H are to be filled with spaces of the common kind, and differing from each other slightly in thickness.

To continue the illustration embraced in this specification, it must be understood that O is filled with hair-spaces and P with five-em spaces, which are to be pressed toward the end plate, u , of the box H by springs. (Not shown the drawings.) There is an aperture made in the bottom of each of the channels O and P next the plate u , just large enough to admit of a single space being passed through into the type-channel. The spaces are prevented from falling through these openings by being pinched or forced against plate u , or by other suitable means. A plunger, v , having a sectional area equal to that of a hair-space, is made to move up and down at the proper times, guided by the spindle w and by the plates of the space-box. This plunger will push single spaces successively from either channel O or P which may be directly beneath it into the opening in the type-line left by its separation. Pinchers x are connected with the piece which carries v , and are shaped as shown in Detail 5, and move up and down with the plunger. The plunger may be made to operate to insert a space without any action of the pinchers on a machine-space; or the insertion of a common space and the extraction of a machine-space may take place during one double stroke of v and x . The rounded or inclined ends of the pinchers open when they strike, in their downward movement, against a machine-space, and in doing this the spring c' , which acts to keep the pinchers together, is extended and causes them to spring into the notches in the ma-

chine-space, by which they acquire a firm hold. It will be obvious that when it is not desired to have the pinchers act to extract machine-spaces any mechanism which will prevent x from catching t' will prevent such action of the pinchers. This is found in the lever a' , upon which are fixed inclined horns y , so that the studs b' may strike the horns y during the movement of the pinchers and open them, so that they will not take hold of the machine-spaces; or the lever a' may be so set that the horns thereon will be placed beyond a chance of contact with the studs, so that the pinchers will open and close upon the machine spaces. It will be observed that the adjacent surfaces of the plunger and pinchers are not in the same plane, because the separation of the type takes place before these instruments act. A couple of bars, d' , are fitted in corresponding apertures in u , and are connected together and to a slide, s' , which is made to move upon the space-box H in the direction of the length of its channels after the pinchers have completed their upward stroke. Whenever the pinchers extract a machine-space, this movement pushes it out of their grasp into the channel in N , from which they may be taken to be used again in the type-setting machine. These bars d' and the slide s' , with which they are connected, are fully illustrated in Detail 8, and are shown elsewhere in the drawings. A compound slide is made to reciprocate at right angles to the line of the movement of the indicating-stop f . This slide moves in suitable bearings or supports, Q , fixed to C , and consists, as is shown in the drawings, and more particularly in Detail 6, of a plain bar, e' , to which bar f' is connected so that it will move with bar e' , unless some obstacle is interposed, e' communicating its movement to f' by the contact caused by the pressure of the spring o' . The parts e' and f' of the compound slide are united by pins in one, passing through slotted holes in the other, in such a manner that when e' moves relatively to f' the parallelism of the pieces shall not be disturbed. Upon the edge of f' , adjacent to the end of the indicating-stop f , an incline is formed, as represented at g' , the length of which must be proportioned to the length of the reciprocation at e' , and the inclination of which must be relative to the thickness of the spaces used in spacing and justifying, and is in the case illustrated four two-hundred-and-seventieths of an inch. At one end of this incline f' is cut away, as shown at h' , sufficiently to admit freely the end of f . The opposite edge of f' is cut away, as shown at i' , which cut should be the sum of the length of the incline g' and the thickness of the pin l . A piece, S , is secured to Q , along which f' moves so closely that any impediment acting at right angles to its line of reciprocation, as part of the compound slide, will clamp f' between S and the impediment, (which is the stop f), so that no strain or binding will take place between f' and e' , and the latter will

continue to move freely, while the former remains stationary.

I will now describe the means by which the space-box is moved over the type-channel so as to bring one or the other kind of spaces which it carries directly over the type-channel. The piece m' is a rocker which acts upon and between two pins fixed in arm j' , which is made fast to the space-box H . The edge of this rocker, where it acts upon the pins in j' , is of sufficient length to remain between said pins throughout the greatest movement which H has to make in order to pass over the longest line of type which the machine is adapted to operate upon. This rocker is made fast to the rock-shaft n' , which is mounted in suitable bearings, w' , and has fixed to it an arm, k' , to which is hinged the rod l' , with a pin, l , projecting therefrom at its upper end. The rod l' has a movement imparted to it, which, if unchecked, would carry the pin at its end from a position below f' to one above it. The parts are so arranged, as shown in the drawings, that when the pin in l' is below f' the hair-space channel O will be over the type-channel, and when above f' the five-em-space channel P will be over the type-channel. Now, a periodic impulse is given l' at the proper time, which, if unchecked, would in its upward movement shift P to the place occupied by O , and in its downward movement would bring O back to the position it occupied at first. It will be evident that l' can thus receive a movement of a fixed maximum extent, and that it can be checked short of that extent by having the motor act upon a spring connected with l' , which is sufficiently rigid to overcome the friction and inertia of the moving parts without yielding, but which will yield sufficiently to permit the motor to move throughout its entire range whenever the pin in l' meets with an obstacle.

Having described the construction of the mechanism, I will now proceed to describe its operation, premising that some normal length of line has been fixed upon, to which the type are to be spaced and justified, and that the length of the line set up does not fall short of its intended normal length more than the length of the vibration of m , which is employed in compressing the spring g before it strikes against o . As the length of the line is determined by the action of the stop f upon the line itself and the compound slide, it may be fixed by adjusting the distance apart of those portions of f which bear upon the type and the part f' of the slide. The stop f being so adjusted, the type set up in line with machine-spaces inserted between each word are introduced into the type-channel, and are held against the stationary stop by spring-pressure exerted through f . The space-boxes and carriage t are placed in position, so that pawl p' impinges against the first machine-space, and then m is made to move till it strikes o , at which time, or just before, the clamps s and q operate, and the balance of the movement of m toward

the compound slide is employed in the separation of the line of type at the machine-space which is operating as a check. Bar e' of the compound slide has previously moved and carried f' with it throughout its movement, provided f has not been brought by the length of the line of type so as to interfere with f' , which it may do by being brought so near to f that the incline g' strikes f before e' has completed its movement in one direction. If the line should happen to be set up of the exact normal length, or within less than the one two-hundred-and-seventieth of an inch of it, then the position of f would be such that it would prevent movement of f' , and that would leave f' in such a position that it would check the upward impulse of l' , which impulse is given after the movement of e' ceases in a direction away from l' . This leaves the hair-space channel over the type-channel, and the position of f , when against g' , may be made to control that of a' , so as to leave the pinchers free to extract the machine-spaces. The plunger and pinchers are then moved down and back again, inserting a hair-space and extracting a machine-space, which, as both are of the same thickness, does not alter the length of the line. The slide s' then receives movement to push the machine-space into N , and the downward movement which the plunger and pinchers receive may be imparted to lever q' to trip the pawl p' , which lets the carriage t , and parts connected therewith, move to the next machine-space, when the clamps release their hold. Those which clamped the movable bar have a slight retractile movement toward the stationary stop. m vibrates back, and the described operations are repeated till the machine-spaces are all extracted, because the length of the line remains unchanged, and so, of course, does the indicating mechanism, and the conditions which produce the movements. When the carriage t has passed over the line, it operates, by its arrival at some fixed point, to throw into gear a mechanism which shall lower the bottom of the type-channel, release the type from the grasp of C , and feed out the line upon a proper galley, which is made to assume a proper position to receive it, after which the type-channel bottom assumes the position in which it is illustrated in the drawings, when another line of type may be introduced and carriage t returned to the first machine-space of the new line. To illustrate the variety of the action of my machine and its automatic adaptation to spacing and justifying, it may be assumed that this new line

falls short of the normal length of the line nearly the full amount admitted in practice. The operations will be as before recited, except that f will not come into contact with f' for some time, during which the whole of the compound-slide will move together, and the pin in l' will strike f' , but on the other side of the recess i' , so that the separation of the line goes on, and the insertion of the hair-spaces, as before described; but the machine-spaces are not extracted, because the mechanism which depresses a' has not been acted upon, the indicating-stop f not being yet in contact with f' . The line may be thus gone over again and again, till, by the insertion of hair-spaces, f is in such a position that the incline g' of piece f' will come into contact with f , when f' will be thereby checked from moving with e' , and the recess i' will be presented so that the pin on l' can pass through, which movement of l' will shift the space-box so that the five em spaces will be over the type-channel. When this movement of l' takes place, it, or some other suitable indication, causes the carriage t , and parts connected therewith, to be returned to the first machine-space. Then, said machine-space is extracted just after a five-em space has been inserted by its side, which increases the length of the line the one two-hundred-and-seventieth of an inch. If the line still lacks one two-hundred-and-seventieth of an inch or more of its normal length, these movements will be repeated, save that the carriage t is not during the operations on this line made to move again toward the compound slide. This operation of inserting a five-em space and extracting a machine-space is continued till the length of the line is so increased by it that f prevents wholly, or nearly so, any movement of f' , which will be when a line lacks less than the one two-hundred-and-seventieth of an inch of its length, when the pin in l' , being below j' , is prevented from moving upward thereby, and the hair-space box being over the type-line, hair-spaces are inserted in the place of the remaining machine-spaces.

I claim—

Justifying lines of type by means of mechanism which operates wholly or partially in the manner substantially as described.

Executed by me at Boston, Massachusetts, December 17, 1860.
